FASTENING DEVICE

Charles B. Greenberg, New York, N. Y.

Refiled for abandoned application Serial No.
78,613 May 8, 1936. This application February 10, 1939, Serial No. 255,690

5 Claims. (Cl. 24—206)

This invention relates to adjustable fasteners, particularly of the type adapted for use on wrist watch straps, belts and the like.

In many devices where adjustable fasteners are employed, it is frequently essential to effectuate variable adjustments either over very small or large ranges, and it is one of the objects of my invention to accomplish this purpose in a simple manner and by employing a readily fabricated and relatively inexpensive structure.

In wrist watch straps particularly, there is need for an adjustable device to accommodate wrists of various sizes, and to produce this result many intricate structures have been devised, some of which contain metallic elements in engagement with the wrist. It is another one of my objects to permit a positive variable adjustment without having any metallic parts touch the skin, and this I accomplish by employing a non-metallic strap containing fastening elements remotely positioned from the wrist.

In certain devices of this class where interlocking elements are employed, there is frequently the danger of a disengagement of the parts during the adjusting operation, particularly where the curvature of the strap or belt is very sharp or pronounced, and it is hence another object of this invention to overcome this shortcoming by enabling the interlocking elements to constantly remain in engagement regardless of the curvature of the embracing band.

Another object of this invention is to facilitate the fabrication of a device of this class by enabling, in one form of my invention, certain fastening elements to be readily aligned and assembled into operative position.

Other objects, features and advantages will appear from the drawing and the description hereinafter given.

40 Figure 1 is a perspective of a wrist watch and strap, showing a few of the fastening elements embodied in my invention on an exposed portion of the band.

Figure 2 is a fragmentary longitudinal cross section of the fastening device constituting this invention when the band is in extended and uncurved condition, the locking element being shown by dot-dash lines in its disengaged position.

50 Figure 3 is a transverse cross section of Figure 2 taken along line 3—3.

Figure 4 is a fragmentary longitudinal end view of the device of Figure 1, showing the band in curved position in accordance with its configuration when positioned about a wrist.

Figure 5 is a perspective view of one of the fastening elements.

Figure 6 is a plan view of a series of fastening elements of modified form, showing their longitudinal disposition upon a band, and

Figure 7 is a plan view of another longitudinal series of fastening elements adapted for use on a flexible band in accordance with this invention, the arrangement shown illustrating an interlocking structure.

In the drawing, the flexible band 8 comprises preferably two layers of material 9 and 10 suitably secured together by mucilaginous or other suitable means. The outer layer 10 thereof has attached thereto a plurality of longitudinally disposed fastening elements 11, these being of H-shaped configuration in the form of my invention shown in Figures 1 to 4. These elements are arranged in close juxtaposition to each other and are preferably contiguous to each other when the band is in uncurved condition as shown in Figure 2. The said elements 11 each contain lateral slots 12 and 13 therein, substantially parallel to the upper and lower faces of the elements, and also contain intermediate recesses 14 and 15 in the forward and rear portions thereof. Each of the said fastening elements 11 is secured to the outer layer 10 of the band by means of the post 16 positioned preferably at the center of the member, the said post extending through suitably spaced holes in the said layer 10 and being secured in operative position by means of the rivets and rings 17 and washers 18. It will be noted, upon an examination of Figure 2, that the layer 10 is compressed between the said washers 18 and the portion of member 11 in facing relation thereto.

When the elements 11 are positioned as aforesaid, they will form two parallel substantially continuous channels or grooves 19 and 20. My invention provides for a slidable element affixed to the overlapping portion 21 of the band adapted to slide within said grooves, said slid able member containing a movable locking element adapted to enter the apertures 22 between the elements 11 formed by the said recessed portions 14 and 15 thereof, for detachable locking engagement, all as will be more fully hereinafter described.

The overlapping or movable portion of the band to which the said slid able member is affixed preferably contains two layers of material 23 and 24, the inner layer being hollowed out to form a central longitudinal recessed portion 25 within which certain parts of the slid able locking member are positioned. Suitably secured to the movable portion of the strap, preferably to the layer 23

thereof, is the housing 26 having an aperture 27 therein to accommodate the release lever 28 pivotally mounted at 29 on the ears 30 and 31 forming preferably an integral part of the slidable channel-like member 32. The said release lever is coextensive with the locking finger 33 adapted to enter the said apertures 22. The said channel-like member 32 contains two inwardly extending legs 34 and 35 positioned within the grooves 19 and 20 and adapted to slidably move therein. It will be noted that the said member 32 actually embraces the lower section 36 of the members 11. The preferred shape of the legs 34 and 35 is slightly arcuate in a longitudinal direction, as can be observed from Figure 2.

In the operation of this device, it will be seen that the locking finger 33 is adapted to enter any of the apertures 22 as aforesaid, thereby preventing the sliding element and the portion of the band to which it is attached from moving in relation to the band 8 under conditions of normal use. The said element 33 is yieldably held in, and urged into, its locking position within the said apertures by the spring 37 which is suitably retained in place by the housing 26. Upon manipulating the movable portion of the band and the said slidable member to the left, in the direction of the arrow (Figure 2), the finger 33 will be forced out of engagement with the aperture when it comes into contact with the recessed wall thereof, causing it to assume the position shown in dot-dash lines in Figure 2, and resulting in a pivotal movement of the releasing lever 28 outwardly. By holding this lever in its projected position, the sliding portion of this device can be manipulated in either direction, the legs 34 and 35 sliding within the grooves 19 and 20 until a predetermined position is reached. Upon a release of the member 28, the spring 37 will urge the finger 33 into one of the apertures 22, and consequently cause the lever 28 to assume its original position flush with the exposed outer surface of the housing 26. Should the finger 33 come to a stop at a point intermediate one of the apertures 22, a slight continued movement will bring it adjacent one of said apertures to permit the spring 37 to operatively actuate it and urge it into locking position. In this manner adjustments can be readily made, it being obvious that the smaller the pitch between elements 11, the more minute the adjustment.

An examination of Figure 4 will show that when the band is curved, the legs 34 and 35 of the channel-like member 32 are still contained, throughout the entire length thereof, within the grooves 19 and 20. This enables a continued sliding movement to be effectuated even with the band curved, there being no possibility of said legs emerging through the spaces 38 between the elements 11. Such spaces 38 are relatively small and are only formed upon a bending of the band, and can readily be dimensionally designed so as to prevent a disengagement of the said legs 34 and 35 from their path of travel within the said grooves 19 and 20.

In the form of my invention disclosed in Figure 6, instead of H-shaped elements 11 Z-shaped elements 39 are employed, causing a staggered arrangement of the abutting edges 40 and 41 of contiguous elements. Upon a curving of the band to which such elements are attached, the spaces formed at such section 40 and 41 will similarly be staggered, thereby preventing the inwardly extending legs of the channel-like member 32 from becoming disengaged from the groove 75 inasmuch as a terminal portion of the one of

said legs will at all times be relatively remote from the spaces at 40 or 41.

In Figure 7 is shown another arrangement where instead of the H-shaped elements 11 of Figure 5 or the Z-shaped elements of Figure 6 interlocking elements 42 are employed, each element containing at one end thereof a recessed portion 43 to receive the extended portion of the contiguous element. In this manner it is apparent that the element can be readily positioned in perfect alignment for best operative functioning.

It will be seen that the invention as described and set forth in the various forms thereof permits of a variable adjustment of a band and which can readily be manipulated at all times. The band is so designed as to keep all metallic elements out of engagement with the object being embraced, and the structure prevents a disengagement of the cooperative elements even upon a bending or curving of the band.

It is of course understood that the various embodiments above described and shown in the drawing are merely illustrative of my invention, and that numerous changes and modifications may be made within the scope of the appended claims without departing from the spirit of this invention.

What I claim is:

1. In a fastening device for flexible band, a plurality of longitudinally disposed fastening elements suitably secured to the band, portions of adjacent elements being in contiguous engagement when the band is in its inoperative unflexed condition, the elements containing recessed portions to form laterally enclosed spaces therebetween, and having slotted portions in the lateral sides thereof to form two parallel substantially continuous longitudinal grooves therein, and a slidable member attached to another portion of the band and containing two inwardly extending legs in slidable engagement with the walls of said grooves and a retractile locking finger adapted to enter any of said spaces and hold said slidable member against movement with respect to said fastening elements.

2. In a fastening device, a flexible band consisting of two layers of material suitably secured together, a plurality of longitudinally disposed fastening elements each containing a post extending through one of said layers and suitably secured thereto, portions of adjacent elements being in contiguous engagement when the band is in its inoperative unflexed condition, the elements containing recessed portions to form laterally enclosed spaces therebetween, and having slotted portions in the lateral sides thereof to form two parallel substantially continuous longitudinal grooves therein, and a slidable member attached to another portion of the band and containing two inwardly extending legs in slidable engagement with the walls of said grooves and a retractile locking finger adapted to enter any of said spaces and hold said slidable member against movement with respect to said fastening elements.

3. In a fastening device for a flexible band, a plurality of longitudinally disposed fastening elements suitably secured to the band, portions of adjacent elements being in contiguous engagement when the band is in its inoperative unflexed condition, the elements containing recessed portions to form laterally enclosed spaces therebetween, and having slotted portions in the lateral sides thereof to form two parallel

substantially continuous longitudinal grooves therein, and a slidable member attached to another portion of the band and containing two inwardly extending legs in slidable engagement with the walls of said grooves, said legs being of slight arcuate contour substantially throughout the length thereof and curved in the general direction of the band when operatively flexed, the terminal of said legs being constantly confined 10 within said grooves, and a retractible locking finger adapted to enter any of said spaces and hold said slidable member against movement with respect to said fastening elements.

4. In a fastening device for a flexible band, 15 a plurality of longitudinally disposed fastening elements suitably secured to the band, portions of adjacent elements being in contiguous engagement when the band is in its inoperative unflexed condition, the elements containing recessed portions to form laterally enclosed spaces therebetween, and having slotted portions in the lateral sides thereof to form two parallel substantially continuous longitudinal grooves therein, and a slidable member attached to another 20 portion of the band and containing two inwardly extending legs in slidable engagement with the walls of said grooves, and a pivotally mounted

lever having at one end a retractible locking finger adapted to enter any of said spaces and hold said slidable member against movement and at the other end a releasing member adapted upon manual manipulation to retract said finger from its locking position and thereby release said slidable member for operative movement. 5

5. In a fastening device for flexible band, a plurality of longitudinally disposed fastening elements suitably secured to the band, portions of adjacent elements being in contiguous engagement when the band is in its inoperative unflexed condition, the elements containing recessed portions to form laterally enclosed spaces therebetween, and having slotted portions in the lateral sides thereof to form two parallel substantially continuous longitudinal grooves therein, and a slidable member attached to another portion of the band and containing two inwardly extending legs in slidable engagement with the walls of 10 said grooves, a retractible locking finger adapted to enter any of said spaces and hold said slidable member against movement, and spring means normally urging said finger into its locking position towards and into said spaces. 15 20 25
